[57] **CLAIM**

The ornamental design for a packaging container, as shown and described.

DESCRIPTION

FIG. 1 is a top perspective view of a packaging container showing my new design;

FIG. 2 is a top plan view, the bottom view being the same in appearance;

FIG. 3 is a side elevational view; and

FIG. 4 is a view partly in section taken on the line 4—4 of FIG. 2.
